Primary Examiner — Kevin K Rudzinski*Assistant Examiner* — Kimberly Barnes(74) *Attorney, Agent, or Firm* — Foley & Lardner LLP(57) **CLAIM**

The ornamental design for a packaging sheet with pattern, as shown and described.

DESCRIPTION

The sole FIGURE is a top view of a packaging sheet with pattern showing our new design.

The depicted surface of the packaging sheet with pattern is flat. The dash-dot lines depict the boundaries of a packaging sheet with pattern and form no part of the claimed design.

1 Claim, 1 Drawing Sheet# US D862,906 S
